ROCKING AND SWIVEL TOY

Carl L. Doerr, Long Beach, Calif., assignor to Doerr Enterprises, Inc., Long Beach, Calif.

Filed Apr. 17, 1962, Ser. No. 69,741

Term of patent 14 years

(Cl. D34—5)

FIG. 1 is a perspective view from one side of a rocking and swivel toy showing my new design therefor; and

FIG. 2 is an elevational view of the other side thereof, on an enlarged scale.

I claim:

The ornamental design for a rocking and swivel toy, substantially as shown.
